UNITED STATES PATENT OFFICE.

^aDAVID G. BLATTNER, OF BOGOTA, NEW JERSEY, ASSIGNOR TO WESTERN ELECTRIC COMPANY, INCORPORATED, OF NEW YORK, N. Y., A CORPORATION OF NEW YORK.

AMPLIFYING WITH VACUUM TUBES.

Application filed June 4, 1921. Serial No. 474,891.

To all whom it may concern:

Be it known that I, DAVID G. BLATTNER, a citizen of the United States, residing at Bogota, in the county of Bergen, State of New Jersey, have invented certain new and useful Improvements in Amplifying with Vacuum Tubes, of which the following is a full, clear, concise, and exact description.

This invention relates to amplifier systems embodying vacuum tubes connected in tandem relation and having a common source of space current, and aims to prevent the amplifier from singing. Further the invention aims to prevent singing in a multi-stage amplifier, wherein one stage is a push-pull amplifier and wherein space current from a common source is supplied, through parallel paths, to the push-pull stage and to a preceding stage. Other and further objects will be apparent from the detailed description hereinafter of the accompanying drawing.

In accordance with the invention as applied to the type of push-pull tandem amplifier circuit mentioned above, a filter is inserted in at least one of the parallel paths or connections from the common space current source to the amplifier stages, in order to prevent the feeding back of electromotive force waves from the output side of the push-pull stage to its input side through the connections for supplying space current.

The accompanying drawing is a diagram of an amplifier circuit embodying the preferred form of the invention.

In the drawing current is supplied from line 1 to line 2, through a multi-stage amplifier circuit, the first stage comprising a vacuum tube 5 and the second stage being a push-pull amplifier comprising vacuum tubes 7 and 9. The two stages are coupled by means of the transformer 11. The push-pull stage is coupled to line 2 by means of a transformer 12.

The filaments of all of the tubes are heated by alternating current from the generator A in accordance with the principles set forth in United States patent application of R. A. Heising, Serial No. 124,953, filed October 11, 1916, entitled Circuit connections of electron discharge apparatus now Patent No. 1,432,022, granted Oc-

tober 17, 1922. Obviously, any other suitable cathode-heating means, as for instance, a direct current source, might be used.

Space current for all of the tubes is supplied from the common source B, the plate circuits of all of the tubes being connected in parallel to each other with respect to the source B. Thus the space current for the tube 5 passes from battery B, through lead 13, primary winding of transformer 11, to the anode of the tube, through the tube to the cathode, and through leads 4 in parallel, the upper and lower halves of impedance 6 in parallel, leads 15, 17, 19 and 21, back to battery. The space current for tube 7 passes from battery B, through lead 23, the upper half of the primary winding of transformer 12, to the anode of the tube, through the tube to the cathode, through leads 8 in parallel, the upper and lower halves of impedance 10 in parallel, and lead 25, back to the battery. The space current for tube 9 passes from battery B through lead 23, the lower half of the primary winding of transformer 12, through the tube, through leads 8 in parallel, through the two halves of impedance 10 in parallel, and through lead 25, back to the battery. Each half of impedance 6, and each half of impedance 10 may consist of a 100 ohm resistance, for instance.

Although the upper and lower halves of the push-pull circuit comprising amplifiers 7 and 9 are generally regarded as balancing each other, so that there is substantially no alternating electromotive force between leads 23 and 25, it has been found that in some cases a considerable alternating electromotive force exists between these leads, especially where the impedance between anode and cathode is not the same in the two tubes 7 and 9. This electromotive force causes a considerable amount of alternating current to flow through these leads and the battery B, since the leads contain no choke coils or other elements of high impedance to current of the frequency of the current being transmitted through the amplifier. Thus, an alternating electromotive force equal to the drop produced in battery B by the alternating current therein is applied to leads 13 and 21, and therefore in accordance with this invention, means are

provided to prevent this electromotive force from sending current waves through the primary winding of transformer 11, and thereby effecting the input circuit of the 5 push-pull amplifying stage and tending to cause this amplifying stage to sing. These means comprise a filter, the filter comprising choke coils 27 and 29 connected in leads 13 and 21 respectively, and a condenser 31 10 connected across leads 13 and 21 and in the output circuit of tube 5. The condenser affords a path of low impedance for the alternating current output of tube 5 and also affords a path of low impedance be- 15 tween leads 27 and 29 for any current waves transmitted to these leads from the junction of leads 23 and 25 with leads 13 and 21 respectively. Choke coils 27 and 29 tend to prevent the transmission of any current 20 waves through leads 13 and 21. Thus, the feeding back of alternating current from the output side of the push-pull amplifier stage to its input side and the singing which would result from such action are prevented. 25 Were it not for the filter, noise or singing might arise from voltage drop in battery B due to the alternations of heating current in the filaments of the push-pull amplifier. Although the push-pull connection tends to 30 prevent the appearance in line 2 of current waves due to the alternations of heating currents in the filaments of the push-pull amplifier by reason of the fact that an increase, say, in current in one half of the primary 35 winding of transformer 12 due to a change of the instantaneous average grid-filament potential and the instantaneous average plate-filament potential in one of the tubes of the push-pull amplifier is accompanied 40 by an increase in current in the other half of the primary winding of transformer 12 due to a corresponding change of the instantaneous average grid-filament potential and the instantaneous average plate-filament 45 potential in this other tube, still, an increase in current in both halves of the primary winding of transformer 12 means an increase of current through leads 23 and 25, and an increase of voltage drop in the battery B; and this increase of drop would act 50 upon the grids of the tubes of the push-pull amplifier through transformer 11, were it not prevented from doing so by the filter. 55 What is claimed is:

1. A vacuum tube amplifier comprising two amplifying tubes connected in a push-pull relation, said tubes having input circuits and output circuits, a vacuum tube, said vacuum tube feeding each of said input 60 circuits, a source, connections for supplying space current from said source to all of said tubes in parallel, and means for preventing a feeding back of current waves from said amplifier tubes to said feeding tube through 65 said connections.

2. A push-pull vacuum tube amplifier comprising two amplifying tubes, said amplifier having input circuits and output circuits, a vacuum tube, said vacuum tube feeding each of said input circuits, a source, 70 connections for supplying space current from said source to said amplifier and to said feeding tube, and a wave filter inserted in said connections and between the output side of said amplifier and the output side of 75 said tube, for preventing said amplifier from singing due to the transfer of energy from its output side to its input side through said connections.

3. In combination, a push-pull electron 80 discharge amplifier comprising control electrodes and space current paths, an electron tube for feeding said amplifier, a transformer coupling said tube and said amplifier for impressing potentials of opposite signs 85 simultaneously upon said control electrodes, respectively, an output transformer for said amplifier comprising a primary winding and a secondary winding, a common source of space current for said tube and said amplifier, a connection for supplying space current from said source to said tube, a connection in parallel to said first mentioned connection for supplying space current from said source to one of said space current 90 paths through one half only of said primary winding and for supplying space current from said source to the other of said space current paths through the other half only of said primary winding, one of said connections being of low impedance for alternating current and said other connection comprising means for preventing said amplifier from singing.

4. A push-pull amplifier, a vacuum tube 105 for feeding said amplifier, a transformer coupling said tube and said amplifier, a common source of space current for said tube and said amplifier, a connection for supplying space current from said source to said tube, a connection in parallel to said 110 first mentioned connection for supplying space current from said source to said amplifier, and a wave filter in one of said connections for preventing said amplifier from singing, said wave filter comprising an inductance and a capacity.

5. A system comprising a vacuum tube, a second vacuum tube for feeding the first mentioned tube, a transformer comprising a 120 primary winding connected to said second tube and a secondary winding connected to the first mentioned tube, for coupling said second tube to the first mentioned tube, an output transformer for said first mentioned tube comprising a primary winding and a secondary winding, a source of space current for said tubes, connections for supplying space current from said source to said first mentioned tube through the primary wind- 125 130

- ing of said output transformer, said connections having low impedance for alternating current, and connections for supplying space current from said source to the other 5 of said tubes through the primary winding of said coupling transformer, said last mentioned connections comprising a choke coil having a high impedance for alternating current.
- 10 6. Electric wave transmitting apparatus comprising a push-pull electron tube amplifier, said amplifier having hot cathode means and having tube input circuits and tube output circuits, an amplifying electron tube 15 having a hot cathode, said tube feeding each of said input circuits, a common source of space current for said amplifier and said tube, and a common source of cathode heating current for said amplifier and said tube.
- 20 7. Electric wave transmitting apparatus comprising a push-pull electron tube amplifier, said amplifier having hot cathode means and having tube input circuits, an electron tube having a hot cathode, said tube feeding each of said input circuits, a common source of space current for said amplifier and said tube, and a common source for supplying cyclically varying heating current to said amplifier cathode means and to said electron tube cathode.
8. Electric wave transmitting apparatus comprising a push-pull electron tube amplifier, said amplifier having hot cathode means and having tube input circuits and tube 25 output circuits, an amplifying electron tube having a hot cathode, said tube feeding each of said input circuits, and means for supplying cyclically varying heating current to said hot cathode means of said push-pull 30 amplifier.

In witness whereof, I hereunto subscribe my name this 2nd day of June, A. D. 1921.

DAVID G. BLATTNER.
